UNITED STATES PATENT OFFICE.

JOHN WHITALL NICHOLSON AND JOSHUA W. GASKILL, OF PHILADELPHIA, PENNSYLVANIA, ASSIGNORS TO JAMES WHITALL, JOHN M. WHITALL, AND JOHN WHITALL NICHOLSON, OF SAME PLACE, JOHN MICKLE, OF MILLVILLE, NEW JERSEY, C. ALBERT TATUM, OF NEW YORK, AND FRANCIS M. UNDERHILL, OF BROOKLYN, NEW YORK.

DESIGN FOR A GLASS OINTMENT-POT.

SPECIFICATION forming part of Design No. 18,836, dated January 1, 1889.

Application filed November 15, 1888. Serial No. 290,941. Term of patent 14 years.

To all whom it may concern:

Be it known that we, JOHN WHITALL NICHOLSON and JOSHUA W. GASKILL, both citizens of the United States, and residents of Philadelphia, Pennsylvania, have invented a new and original Design for a Glass Ointment-Pot, of which the following is a specification.

Our design for a glass ointment-pot is fully illustrated in the accompanying drawing, which represents a side view of the pot with a screw-cap therefor shown above the same.

A is the body of the pot, cylindrical in form, and having vertical sides *a a*, a raised band, *b*, forming a base, and a raised band, *d*, near the upper end. At the extreme upper end of the pot is a beveled edge, *e*, and between this

beveled edge and the raised band *d* are inclined ribs *f*, one projecting inward from one side of the pot and the other from the opposite side of the same, as clearly shown.

We claim—

The design for a glass ointment-pot, substantially as described, and as shown in the accompanying drawing.

In testimony whereof we have signed our names to this specification in the presence of two subscribing witnesses.

JOHN WHITALL NICHOLSON.
JOSHUA W. GASKILL.
